UNITED STATES PATENT OFFICE

CLAYTON L. DAY, OF NEW YORK, N. Y., ASSIGNEE TO CHICAGO BRIDGE & IRON CO., A CORPORATION OF ILLINOIS

STORAGE TANK FOR VOLATILE LIQUIDS

Application filed December 29, 1927. Serial No. 243,226.

This invention relates to improvements in storage tanks for volatile liquids, and more especially to such a tank of the "breather" type to permit expansion and contraction of the gases in the vapor space above the liquid without loss. For example, in tanks of this type used for the storage of gasoline, crude oil, and other volatile liquids, there is a considerable amount of gas in the space above the liquid. Variations in temperature cause changes in this volume and if the volume of the container cannot change accordingly there is an escape of gas and consequent loss.

One of the features of my invention is the provision of such a tank requiring no mechanical valves and presenting no drainage problem. The tank, nevertheless, permits expansion and contraction of the gases in the vapor space above the liquid while effectually sealing the tank at all times against the escape of gases into the atmosphere.

Another feature of my invention is the provision of improved means for guiding the roof in its vertical movements.

Another important feature of my invention is the fact that it may be employed in connection with standard tanks now in common use not of the breather type. Such tanks may be easily converted into my improved storage tank by slight adaptations.

Other features and advantages of my invention will appear more fully as I proceed with my specification.

In that form of device embodying the features of my invention shown in the accompanying drawings, Figure 1 is a vertical sectional view, Fig. 2 is a fragmentary view similar to Fig. 1 showing the liquid seal on an enlarged scale, Fig. 3 is a fragmentary view similar to Fig. 1 on an enlarged scale showing the central guide for the movable roof, Fig. 4 is a view taken as indicated by the line 4 of Fig. 1, Fig. 5 is a view similar to Fig. 1 showing a modified form, Fig. 6 is a view similar to Fig. 2 showing a modified form, and Fig. 7 is a view similar to Fig. 2 showing a modified form of the vertical guide.

As shown in the drawings, the tank comprises the usual cylindrical shell 10 with the bottom 11. Such tanks not of the breather

type now in common use are frequently provided with a stationary conical roof. Such a tank may be easily converted into my improved breather tank by cutting the conical roof from the shell. Such a roof is indicated by 12. 13 indicates a trough built around the top of the shell which may be either on the outside as shown in Fig. 1, or on the inside of the shell as shown in Fig. 6 by 13^a. The trough is filled with liquid 14 which, for example, may be water in warmer climates or brine in colder ones. The roof 12 is provided at its periphery with a depending flange 12^a having its lower edge immersed in the liquid 14, thus providing a liquid seal between the shell and the roof.

Suitable guiding means are provided to guide the roof in its vertical movements. Such means may include members such as the rollers 15 carried by the roof and engaging the inner wall of the shell 10. The rollers 15 may be supported in any suitable manner as, for example, by means of the diagonal hanger bars 16 and the vertical rod 17 provided with turn buckles 18 to raise or lower the rollers 15 to swing the rod 16 on the pivots 19 to bring the rollers 15 into correct adjustment against the shell 10. There may also be provided central guiding means including a post 20 the upper end of which is telescopically embraced in the cylindrical guide 21 on top of the roof (see Fig. 3). There may be provided a collar 21^a inside of the shell 21 to lessen the length of the sliding surface.

22, 22 indicate suitable rafters supported by the posts 23 to take the weight of the roof 12 in its lowermost position.

In Fig. 5 I have shown a modified form in which the trough for the liquid seal is located inwardly a short distance. In this modified form, the top of the shell 110 may be provided with a narrow stationary inwardly extending flange 110^a and the trough 113 may be at the inner margin of this flange 110^a. 95 In such construction the conical roof 112 is preferably provided at its periphery with an upwardly extending flange 112^a and this in turn with an outwardly extending flange 112^b carrying at its periphery the depending 100

flange 112^a with its lower edge immersed in the liquid 114 in the trough 113^a. In converting a tank with a stationary conical roof into my improved breather type of tank, it may be easier to cut the roof on a line in a little distance from the outer edge of the tank instead of at the very outer edge.

In the modified form shown in Fig. 7, I have shown additional guiding means comprising the vertical guide members 24^a and the rollers 24 mounted on the periphery of the roof, said rollers moving up and down on the guides 24^a with the movement of the roof 12.

As shown in Fig. 2, the roof 12 may be provided with a projecting eave 12^b to prevent rain water from entering the trough 13.

While I have shown and described certain embodiments of my invention, it is to be understood that it is capable of many modifications. Changes, therefore, in the construction and arrangement may be made without departing from the spirit and scope of the invention disclosed in the appended claims, in which it is my intention to claim all novelty in my invention as broadly as possible in view of the prior art.

What I claim is new, and desire to secure by Letters Patent, is:

1. A storage tank comprising; a substantially cylindrical shell; a vertically movable roof; a liquid seal between the shell and the roof of relatively slight height with respect to the height of the tank; and guiding means for guiding the roof in its vertical movements, said guiding means including members carried by the roof engaging the inner wall of the shell and said guiding means extending inwardly a substantial distance from the margin of the roof to constitute effective brace elements for the latter.

2. A storage tank comprising; a substantially cylindrical shell; a vertically movable roof; a liquid seal between the shell and the roof; and guiding means for guiding the roof in its vertical movements, said guiding means including members carried by the roof engaging the inner wall of the shell, said members being supported from said roof by diagonal outwardly, downwardly extending hanger bars and vertical adjustable rods connecting the outer ends of said hanger bars to the roof, said diagonal hanger bars being extended inwardly a distance from the margin of the roof to constitute effective brace elements for the latter.

3. A storage tank comprising; a substantially cylindrical shell; a vertically movable roof; a liquid seal between the shell and the roof; guiding means for guiding the roof in its vertical movements, said guiding means including members carried by the roof extending a substantial distance inwardly from the margin of the roof to constitute effective braces for the latter and engaging the inner wall of the shell; and means for adjusting

said last mentioned members individually inwardly or outwardly to vary the pressure of their engagement with the inner wall of the shell.

4. A storage tank comprising a substantially cylindrical shell, said shell at the top thereof having a stationary roof portion extending inwardly from the margin, a vertically movable roof substantially inwardly of said portion, one of said parts having a downwardly extending flange, the other of said parts having a trough adapted to contain liquid engaged by said flange.

5. A storage tank comprising a substantially cylindrical shell, a vertically movable roof substantially of conical form, a liquid seal at the junction of the shell and roof, guide means carried by the roof and engaging the shell below the liquid seal, said guide means extending inwardly and connected to the roof at a substantial distance from the margin thereof so as to form an effective brace means, and a central guide means co-acting with the brace means to preserve the shape of the roof, comprising a cylindrical guide member extending upwardly from the apex of the roof and post means within and engaged by said cylindrical member.

In witness whereof, I have hereunto set my hand this 12th day of December, 1927.
